MINI-BIKE SHAPED SEAT FOR PLAYGROUND APPARATUS

Robert S. Wormser, Hillsdale, Mich., assignor to Game Time, Inc., Litchfield, Mich.

Filed Nov. 1, 1971, Ser. No. 194,800

Term of patent 14 years

Int. Cl. D21—03

U.S. Cl. D34—5 L

FIG. 1

FIG. 2

FIG. 3

FIG. 1 is a side, elevational view of the left side of a mini-bike shaped seat for playground apparatus in accord with my new design, the right side being identical thereto in appearance,

FIG. 2 is a front, elevational view,

FIG. 3 is a top plan view in accord with my new design, and

FIG. 4 is a rear, elevational view.

I claim:

The ornamental design for a mini-bike shaped seat for playground apparatus, substantially as shown and described.
